UNITED STATES PATENT OFFICE.

LUDWIG NEUMAYER, OF MERSEBURG, GERMANY.

ADVERTISING-VEHICLE.

SPECIFICATION forming part of Letters Patent No. 676,822, dated June 18, 1901.

Application filed June 1, 1900. Serial No. 18,753. (No model.)

To all whom it may concern:

Be it known that I, LUDWIG NEUMAYER, a subject of the German Emperor, and a resident of Merseburg, Germany, have invented 5 certain new and useful Improvements in Advertising-Vehicles, of which the following is a specification.

The object of my present invention is to provide an advertising-vehicle the back and 10 sides of which are made of transparent material, the advertisements or the like being projected upon the back wall by means of devices arranged in the interior of the vehicle.

In the accompanying drawings, forming a 15 portion of the specification, Figure 1 is a vertical sectional view, and Fig. 2 is a horizontal sectional view, of the improved advertising-vehicle.

The side and back walls of the vehicle are 20 formed of plates *a*, made of glass or other transparent material. The vehicle contains a magic-lantern *b*, which projects the advertisements upon the back wall, as above stated. The advertisements may be stationary or 25 changed and varied by means of plate *c*, which may be moved forward automatically by means of any suitable device. The plate *c* in construction and operation is exactly similar to the slide of an ordinary magic-lantern, and 30 therefore needs no special description. Mov- able advertisement-pictures may also be sub- stituted therefor. The side walls of the ve- hicle are protected from the light of the lan-

tern by means of intermediate walls *d* and are lighted or illuminated intermittently or 35 constantly, as desired, by means of electric incandescent lamps *g* *g*, receiving the current from a common storage battery *A*, ar- ranged on the floor of the vehicle or elsewhere therein. Said lamps may be of different col- 40 ors, and devices may be provided to enable the same to be cut in and out, as desired, during the progress of the vehicle.

l l represent the current-conducting wires.

The vehicle may be moved in any desired 45 way and constructed in the form of a motor- car.

Having fully described my invention, what I claim, and desire to secure by Letters Pat- ent, is—

The improved advertising-vehicle comprising transparent side and back walls made of suitable material, a lantern in the interior of the vehicle and adapted to project advertise- ments upon the back wall of the vehicle and 55 intermediate walls protecting the side walls from the light of said lantern, said side walls being lighted or illuminated as desired, by means of electric incandescent lamps, sub- stantially as and for the purpose set forth. 60

In testimony whereof I have hereunto set my hand in presence of two witnesses.

LUDWIG NEUMAYER.
